UNITED STATES PATENT OFFICE.

DANIEL HOYT, OF EAST ORANGE, NEW JERSEY, ASSIGNOR OF ONE-HALF TO THE NATIONAL LOCK WASHER COMPANY, OF NEWARK, NEW JERSEY, A CORPORATION OF NEW JERSEY.

SASH-LOCK.

1,253,826.

Specification of Letters Patent.

Patented Jan. 15, 1918.

Application filed August 15, 1912. Serial No. 715,312.

To all whom it may concern:

Be it known that I, DANIEL HOYT, a citizen of the United States, residing in the city of East Orange, in the county of Essex and 5 State of New Jersey, have invented certain new and useful Improvements in Sash-Locks, of which the following is a full, clear, and exact description, such as will enable others skilled in the art to which it pertains 10 to make, construct, and use the same, reference being had to the accompanying drawings, and to letters of reference marked thereon, forming a part of this specification.

This invention relates to new and useful 15 improvements in that class of sash locks in which the sash is held in any desired position in the window frame, by the engagement of cams in the locks with metallic strips on the window frame, said cams being released by finger pieces.

One of the objects of this invention is to provide a sash lock with but a single cam, which will be compact, neat in appearance, simple and inexpensive in construction, and 25 which will perform practically all the functions of a double cam sash lock.

A further object of this invention is to provide a sash lock which will not only lock the sash in the lowered position, but one 30 which is adapted to force the sash tightly on the window sill, thereby excluding dust and air.

Other objects will appear from the description hereinafter given, and my invention 35 consists in the combinations and arrangements of parts which will be herein-after fully described and specifically defined in the appended claims.

In the drawings forming a part thereof, 40 Figure 1 represents a front view of a window containing my improved sash locks and racks.

Fig. 2 represents a horizontal sectional view on line $x-x$ of Fig. 1.

Fig. 3 represents one corner of a sash, with the sash lock attached, a portion of the rack being broken away to more clearly illustrate the detailed construction thereof.

Fig. 4 represents a front elevation of my 50 improved lock.

Fig. 5 represents a plan view of the metallic strip.

Fig. 6 represents a cross-sectional view 55 of the metallic strip taken on line $x-x$ of Fig. 5.

Fig. 7 represents a sectional side elevation of the metallic strip, and

Fig. 8 represents a cross-sectional view of the metallic strip taken on line $x'-x'$ of Fig. 5.

Similar letters of reference refer to like parts throughout the specification and drawings.

Referring to the drawings A represents the sash, B the window casing, and C the window sill. The sash lock which may be secured to the window sash in any well-known manner consists essentially of the metallic casing a provided with a removable cover plate, not shown. b represents a fixed 65 pivot or axis, and c represents a cam lever adapted to partially revolve on said pivot or axis b . The outer portion of the cam lever c or the part adjacent the window frame A, is provided with an engaging face d , said engaging face d being located below the pivot or axis b , and is formed at an acute angle to the plane of the lever, as clearly indicated in Figs. 2 and 4 of the drawings. The lower portion of the engaging face d 70 is formed with a tooth e adapted to engage with a slot in the metallic strip to be presently described. This portion of the engaging face may be provided with one or more teeth as desired.

The engaging face d is provided with a hook-shaped portion f . The top of the cam lever c is provided with a shoulder g , which is designed to contact with the upper portion of the metallic case a to limit the outward movement of the cam lever. The casing a is further provided with a fixed center post h , which forms a fulcrum for the arms of the spiral-coiled spring i , to which the removable cover plate is secured. One arm 80 of the spiral-coiled spring i bears against the rear wall of the casing a and the other arm bears against the inner lower portion of the cam lever c , tending at all times to force the same outward and upward. The 85 cam lever c is also provided at its inner end, which projects outside of the casing a , with an integral operating lever or finger piece j , formed by widening said inner end. This finger piece j is of approximately the same 90 configuration as the finger piece k , which is formed integral with the metallic casing a . The edge of the casing a nearest the window casing is provided with an outwardly extending guide l , designed to engage with the 95

edge of the metallic rack, to be presently described. This guide *l* is preferably formed integral with the casing and may extend the entire length of the casing or only part of 5 the length, as desired.

m represents the metallic strips which are secured to the window casing *B* and set at an angle to the plane of the sash *A*. The metallic strip *m* with which the engaging 10 face *d* of the cam lever *c* engages, is provided with slots *n* on its upper portion, while the lower portion is provided with a smooth surface *o*, and near the bottom of the strip at a point adjacent the tooth *e* of the 15 cam lever *c* when the sash is closed, is another slot *n*. These slots are formed with a shoulder *p* at the lower end, and the upper end of the slot is provided with a downwardly projecting hook *q*, to correspond 20 with the hook-shaped portion *f* of the engaging face *d* of the cam lever *c* with which the latter is adapted to engage. The front edge of the metallic strip *m* is provided with a guide or smooth portion *r*, said smooth 25 portion or guide extending the entire length of the strip.

By referring to Fig. 2 of the drawings, it will be noted that the metallic strip *m* is set at an angle to the plane of the sash, and 30 that between the metallic strip *m* and the sash *A*, a wide angular gap exists, the width of the mouth of this gap, together with the lateral freedom of the sash between the inside and outside stops, being sufficient to let 35 the edge of the ordinary sash lock case enter, when the sash is being raised or lowered, thereby causing the lock case to jam in this angular gap or wedge-shaped opening, causing the upper or lower edge of the metallic 40 casing *a* to catch in the slots *n* in the metallic strip, and also allowing the sash to have excessive side movement, all of which causes a very unsatisfactory working window.

45 In order to obviate these difficulties, I form the edge of the metallic strip, next to the sash lock with a smooth portion *r*, and also provide the casing *a* with an outwardly extending guide *l*, designed to engage with 50 the smooth portion of the metallic strip, when the sash is pushed out against the outside stops, at which position of the sash the mouth of the angular gap is at its maximum width, thereby preventing the lock 55 casing from entering the angular gap, and at the same time, providing accurate guiding means for the sash.

60 In assembling the metallic strips and locks on the window, I first secure the metallic strips *m* to the inside sash stops at an angle to the face of the sash as shown in Fig. 2, with the smooth portion *r* of the strip extending to or slightly above the face of the stops of the window frame.

65 The sash is then set squarely in the win-

dow frame, so that neither side edge thereof will contact with the window frame at the bottom of the guide-ways as clearly shown in Fig. 2; the locks are then secured to the sash, one near the lower right-hand corner 70 and the other near the lower left-hand corner, with the guide *l* on the lock casing *a* in close proximity to the guide or smooth portion *r* of the metallic strip *m*, thus forming guides to maintain the sash centrally 75 in the window frame.

The lock should be placed in such a position on the sash that the tooth *e* of the cam lever will enter the slot *n* in the metallic strip, and be forced up, so that the hook-shaped portion *f* of the cam lever will engage with the downwardly projecting hook *q* of the metallic strip *m* by the force of the spiral coiled spring *i*, and as said spring is constantly forcing the tooth *e* with its hook-shaped portion *f* upward, it will simultaneously force the sash downward on the window sill, thereby forming a tight joint between the lower edge of the sash and the sill.

When the finger pieces *j* are compressed, the engaging faces *d* of the cam levers *c* are drawn within the lock casing *a*, and the sash is free to be raised or lowered. When the sash is to be held in elevated position, the finger pieces are released, and the tooth *e* enters one of the slots *n* and the weight of the sash will cause it to move in the closing direction until the under side of the tooth *e* on the cam engages the shoulder *p* at the bottom of the slot *m*, the weight of the sash causing the cam to rotate and wedge itself firmly against the rack. The heavier the sash the tighter it will wedge or lock the cam in engagement with the rack. The force of a spring is not required for the locking action to maintain the sash in elevated position, the spring simply serving, under these conditions, to throw the tooth *e* promptly into the slot of the rack. If any attempt is made to raise the sash without first compressing the finger pieces, the hook-shaped portion *f* of the cam lever will engage the downwardly projecting hook *q* of the metallic strip, thereby preventing the sash from being further raised without compressing the finger pieces.

When the sash is near its closed position, as indicated in Fig. 1 of the drawings, the engaging faces *d* of the cam levers *c* only bear against the smooth surfaces *o* of the metallic strips *m*, and then only act as brakes, but will allow the sash to settle down upon the window sill until the hook-shaped portions *f* enter the lower slots in the metallic strips, when they will constantly crowd the sash down on the sill.

Inasmuch as the metallic strips are placed at an angle to the plane of the sash, and inasmuch as the engaging faces of the cams

are formed at a corresponding angle, the tendency is to force the sash outward against the outside stops, making a tight joint, excluding air and dust, preventing lateral 5 movement of the sash and also preventing rattling thereof.

While I have shown my preferred form, it will be understood that many changes may be made without departing from the spirit 10 and scope of my invention, as for instance, the slots in the metallic strip may be arranged closer or farther apart, or if a balance is used for the sash, slots might be dispensed with, except such as are necessary 15 to lock the sash down. The metallic strip may be made in any form, and may be set squarely on the window frame, as shown in Fig. 3 of the drawings.

I claim:

20 1. In combination with a window frame, a sill, a sash provided with means for positively locking it in its closed position, and a spring acting through the locking means to continuously press said sash yieldingly 25 upon said sill.

2. In combination with a window frame, a gravity sash freely slideable therein and constructed to rest by gravity in contact with the window sill, a metallic strip secured 30 to the window frame and having a downwardly projecting hook-shaped member extending at right angles to the length of said strip, a sash lock secured to the sash and having a lever carrying an upward 35 hook-shaped member, and a spring to force the hook and the lever outward and upward in engagement with the hook on the said strip to hold the sash down in contact with the window sill, said hook-shaped member 40 continuously engaging said hook on the strip while the sash contacts the window sill.

3. The combination with a window frame and window sill, a gravity sash adapted to 45 slide freely therein, a metallic strip secured to the window frame, said rack having a smooth unbroken plane face and a single socket near the lower end of the strip, said socket having an upper wall formed at right 50 angles to the length of the rack, said top wall being undercut forming a downwardly inclined hook-shaped member, a sash lock secured to the sash comprising a case having an integral finger piece, a pivot post 55 within the case, a cam lever pivoted on the post, said cam lever having a head adapted to engage the smooth portion of the rack and to act as a cam friction brake on the smooth portion of the rack during descent 60 of the sash by gravity, a spring within the case to force the engaging portions of the cam lever into engagement with the un-

broken plane face of the rack, the engaging portion of the cam lever and the pivot of the latter being so arranged that said engaging 65 portion is held in strong frictional engagement with said face of the rack by the weight of the sash, and means formed on said cam lever to engage the upper wall of the socket in the rack whereby the action of 70 the spring on said lever forces the sash downward on the window sill.

4. The combination with a window frame, a sash adapted to slide therein, metallic racks secured to the window frame at an 75 acute angle to the plane of the sash and having sockets formed therein, said sockets having upper and lower walls formed at right-angles to the length of the rack and a back wall between the upper and lower walls 80 of the sockets, said sockets being open at one end, said rack being further provided with a continuous guide surface the entire length of one edge and closing one end of each of the slots, a sash lock secured to each 85 side of the sash, each lock comprising a case having an integral finger piece, a cam lever pivoted within each case, one portion projecting from the case forming a finger piece, another portion having an engaging 90 head formed at an acute angle to the plane of the lever adapted to engage the face of the rack or back wall between the sockets, said head being provided with a locking tooth below the pivot adapted to engage 95 the lower wall of the socket to lock the sash against falling, the case of each lock being further provided with a guide extending laterally from the case and along one edge thereof adapted to engage the guide surface 100 of each rack by which means the sash is maintained central in the window frame, and preventing the lock case from catching on the sockets in the rack, and a spring 105 within the case to actuate the cam lever.

5. In combination with a window frame, a sash adapted to slide therein, a metallic strip secured to the window frame and having a downwardly projecting hook-shaped member extending at right angles to the 110 length of the strip, a sash lock secured to the sash having a lever carrying an upward hook-shaped member, and a spring to force the hook of the lever outward and upward in engagement with the hook on the strip, 115 whereby the sash is held yieldingly down on the window sill.

This specification signed and witnessed this 8th day of August, 1912.

DANIEL HOYT.
